TAPPET HOLDING WRENCH

Charles E. Johnson, North Muskegon, Mich., assignor to Johnson Products, Inc., Muskegon Heights, Mich., a corporation of Michigan.

Application January 21, 1946, Serial No. 642,538

2 Claims. (Cl. 81—3.02)

1

This invention relates to a tappet holding wrench, and is concerned with the improvement and simplification of wrenches of the character mentioned such as shown in my pending application for Patent Ser. No. 628,236, filed November 13, 1945.

As described in said pending application, the adjusting of tappets to proper length between a cam on a cam shaft and the lower end of a valve stem requires a holding of the tappet body from turning, this heretofore having been generally done by use of a wrench which must be held by one hand of the mechanic; while the tappet screw screwed into the upper end of the body is turned in the selected direction by a second wrench manipulated by the mechanic with his other hand. In the present invention, as the disclosure shown in my pending application, a holding wrench has been devised which spans the space between two adjacent tappets, may be very quickly connected therewith or removed, and which holds the tappet body of the tappet adjusted firmly and securely against turning about its longitudinal axis, thereby freeing one hand of a mechanic; with a resultant much better and easier accomplishment of tappet adjustment which, at the best, is a somewhat difficult operation. Such operation is attained much easier and more satisfactory by the use of my invention which, when used, holds a tappet which is being adjusted with certainty and absolute assurance that it will not turn about its longitudinal axis to any extent or degree whatsoever, thereby eliminating the uncertainty of the human factor occurring when the tappet body is held against such turning movement by a manually held wrench.

The invention likewise is adapted for use in conjunction with substantially all, if not all, motor vehicle internal combustion engines, and is available for use in the very circumscribed spaces which many engines have, there being no requirement for changing the over-all lengths of the tappets in engines built and in service.

The construction of tappet wrenches which I have devised is applicable to a make of a V-8 engine, in which initially the tappets are nonadjustable, and have a preselected length which cannot be changed for replacement or for servicing engines of such character. I have devised a mechanically adjustable tappet for the initially

2

installed nonadjustable tappets which, as to its body portion, is shorter than the original tappet used in the engine, and has an adjustable screw, threaded into the upper end of the tappet body, the overall length of the adjustable tappet from the lower end of the body to the upper side of the head of the screw being substantially the same as that of the non-adjustable tappet which it replaces. And, inasmuch as the space between 5 the tappet guide and the valve mechanism above is very limited so that it is not possible to provide a tappet body with the usual flat sides at its upper end, for engagement by a wrench to hold it against turning around, such wrench engaging surfaces at the upper end of the tappet body are eliminated, and a novel means for connecting the wrench of my invention with a body of a tappet to be adjusted and also with the tappet next adjacent thereto has been devised.

10 In my prior application, the tappet to be adjusted was disposed in its lowermost position, and the one next adjacent in a higher position, necessitating a turning of the engine cam shaft until such prescribed positioning of two adjacent tappets occurred. In the present invention such positioning of two adjacent tappets is not required, but a tappet may be adjusted when held by the wrench of my invention with the next adjacent tappet at the same height. Furthermore, in the 15 present invention no separately made and assembled retaining or locking member is required, there being an elimination of such retaining or locking member as a securing means used and movably mounted upon the body of the wrench. This reduces the structure to its simplest and 20 most economical form, thereby very appreciably lessening manufacturing cost.

An understanding of the invention may be had from the following description, taken in connection with the accompanying drawing, in which,

Fig. 1 is a fragmentary, substantially horizontal section taken through the upper part of an internal combustion engine and over the upper ends of the tappets and their guides, showing the 25 tappet wrench connected at one end to the body of the tappet to be adjusted, and operably connected at its other end with the next adjacent tappet screw.

Fig. 2 is a longitudinal vertical section substantially on the plane of line 2—2 of Fig. 1.

Fig. 3 is a fragmentary vertical section substan-

tially on the plane of line 3—3 of Fig. 1, both sections looking in the directions indicated by the arrows.

Fig. 4 is a perspective view of the tappet wrench.

Fig. 5 is a fragmentary enlarged plan and horizontal section, showing the shank of a tappet screw and the formation of the opening or recess in a tappet wrench to receive it.

Fig. 6 is a view similar to Fig. 1, with the wrench as designed for the tappet adjustment revised, and modified in form for such revision.

Like reference characters refer to like parts in the different figures of the drawing.

The tappet wrench of my invention is made from a single plate of flat metal. It has a body portion 1 of a generally trapazoidal form and with diverging side edges, and at the wider side of the body an arc shaped section 2 is preferably depressed, surrounding a generally arc shaped recess 3, open at its outer side, the detail of the specific form of which will be later described. At the same side of the body 1 it is extended as an arm 4 a short distance and then directed backwardly at an angle, as indicated at 5, at its free edge having a tongue 6 bent downwardly at right angles, the vertical edges of which are preferably serrated though not necessarily so. From adjacent the depressed section 2 to the section at 5, a reinforcing and strengthening flange 7 is bent upwardly at right angles. Such flange may be further extended and turned to lie alongside of the edge of the end portion 5, if for reasons of strength it may seem desirable. The body 1 adjacent its outer end preferably has an opening 8 therethrough, shown as of circular form.

The recess at 3 having an open side is of a special form as shown in Fig. 5. The angle of the edges 9 and 10 at each side of the recess is less than a straight angle and the meeting of lines projected toward each other from the edges 9 and 10 is substantially at the center of the recess 3, the inner side of which is at a point indicated at 11, so that if a true arc was struck from said center, any body circular in cross section to enter said recess, would be of a diameter less than the diameter of the arc shaped recess made. In the construction of the wrench which I have devised, the bottom of the inner edge of the recess at 11 is slightly flattened and the metal is cut away at both sides of the recess as indicated in 12, substantially to form arcs of a circle of substantially the same radius as a body having a circular cross-section which will pass between the pointed portions at 13 between the outer end of the arcs 12 and the angularly disposed edges 9 and 10. Therefore, the shank 14 of a tappet screw, having a head 15 screwed into the upper end portion of the tappet body 16, will enter such recess freely and with the tongue 6 anchored in a downwardly bored recess 17 in the upper end of the next adjacent tappet body, wrench pressure applied to the head 15 of said next adjacent tappet screw will move the device so that either one arc 12 or the other will come into engagement with the cylindrical surface of the shank 14 adjacent the ends of the arm 12 engaged. Which of the arc shaped edges 12 will thus grip or engage with the surface of the shank 14 of a tappet screw depends upon which direction the screw of the next adjacent tappet is turned. In either case there is provided a secure holding of the device in place, and with no possibility of disengagement so long as turning pressure is exerted upon the tappet screw of the tappet which is being adjusted.

The tappet bodies 16 of tappets of internal combustion engines are mounted in suitable guides of cylindrical form made in the engine block 18. As is conventional practice, the lower end of the body 16 of each tappet rides upon or bears against a cam 19 of an engine cam shaft 20.

As shown in Fig. 1, the wrench device of this invention is applied by grasping it between the thumb and first finger at the opening 2, passing the extension 4 between two adjacent tappets and locating the downturned tongue 6 in one of the series of openings 17 made at the upper end of each tappet body 16. While four of said openings 17 are shown, the number may be increased or diminished without changing the invention. When the tongue 6 has thus been located in an opening 17 of one tappet body, the body portion 1 is moved inwardly so that the recess at 3 receives the shank 14 of the tappet screw next adjacent. The body 16 of the tappet engaged by the tongue 6 may be moved about its vertical axis to bring said recess at 3 to proper position to receive the screw shank 14.

A wrench may now be applied to the head 15 of the tappet screw of the tappet engaged and held by the tongue 6, and the screw may be turned in either direction, with an immediate slight movement of the wrench device of this invention so that one of its arc shaped edges at 12 engages the adjacent curved surface of the screw shank 14. Continued turning of the tappet screw by the wrench engaged therewith maintains a continuous pressure against the shank 14 of said next adjacent tappet screw, thus retaining the shank 14 within the recess 3 positively, and preventing any disengagement therefrom. And if the turning of the tappet screw engaged is reversed there is a small bodily movement of the body 1 bringing the other or opposite arc shaped edge 12 against the opposite side of the shank 14 of the screw which is in the recess 3.

In Fig. 6, the tappet wrench which I have produced, is the same as in Fig. 1, except it is reversed. That is, for an engine two of the tappet holding wrenches of my invention are required in order that all of the tappets of an engine may be adjusted. The tappet shown does not enter into detail of structure of a self locking character of the screw used, as this forms no part of the present invention, and may be of several well known construction types, some of which have been devised by me, as shown for example, in my Patent No. 2,361,107, issued October 24, 1944. The invention however, is not in any sense limited to the use of the self-locking tappet screw of the patent mentioned.

With the construction described a tappet holding wrench of the simplest form has been produced, eliminating the locking member shown in my prior application. The tappet wrench of my invention is instantly applied, falls naturally into place in engines of the V-type, because of its simplicity of structure is very economically produced and with the difficult operation of adjusting tappets is much more quickly and easily performed.

The invention is defined in the appended claims and is to be considered comprehensive of all forms of structure coming within its scope.

I claim:

1. A tappet holding wrench comprising a flat metal body widened at one end and having at a side edge thereof a recess to receive the shank of a screw of a tappet, said body at its opposite

end having a downturned tongue adapted to be inserted into a hole at the upper end of the next adjacent tappet, said recess having an entrance opening through the edge of said body through which said shank may pass, the width of said entrance opening being less than the diameter of said recess whereby to partially embrace said shank of said screw.

2. The elements of claim 1 in which the metal of the body surrounding said recess is offset downwardly in the same direction as said tongue extends.

CHARLES E. JOHNSON.
